UNITED STATES PATENT OFFICE.

JOHN H. STEWART, OF WATERLOO, IOWA, ASSIGNOR TO STEWART CEMENT BLOCK MACHINE COMPANY, OF WATERLOO, IOWA.

MACHINE FOR FORMING CONCRETE BUILDING-BLOCKS.

SPECIFICATION forming part of Letters Patent No. 777,557, dated December 13, 1904.

Application filed May 24, 1904. Serial No. 209,438. (No model.)

To all whom it may concern:

Be it known that I, JOHN H. STEWART, a citizen of the United States of America, and a resident of Waterloo, Blackhawk county, 5 Iowa, have invented certain new and useful Improvements in Machines for Forming Concrete Building-Blocks, of which the following is a specification.

My invention relates to improvements in 10 machines for forming concrete building-blocks; and the objects of my invention are to more particularly effect improvements in my machine which was patented by me on September 1, 1903, under No. 737,881, by 15 adding means whereby the core may be withdrawn from the mold when desired independently of the ordinary action, and to also otherwise simplify the construction by eliminating certain elements and substituting others, and 20 by providing means for adjusting the size of the mold as desired.

These objects I have attained by the mechanism which is hereinafter described and claimed and which is illustrated in the drawings hereto annexed, in which—

Figure 1 is a side elevation of the machine, and Fig. 2 is an end elevation of the same.

Similar numbers refer to similar parts throughout both views.

My said machine has a mold with drop sides 32 33 37 38 and vertically movable and removable bottom plate 72. This bottom plate 72 is provided with rectangular openings for the passage therethrough of cores 30 31. Side 35 pieces 23, which are provided with slots 28 29, the latter being bearings for the studs 26 27 on the inner arms 24 and 25 of the drop-braces 39 and 41, depend from the rack-frame 49. The drop-braces 39 and 41 are adjustably connected to the end plates 37 and 38 by the bolts 43 44 and 47 48, respectively. Said drop-braces are also pivoted in uprights attached to the machine-frame at 53 and 55, respectively. The drop-braces 56 57 are 40 respectively adjustably connected to the side plates 32 33 by means of the bolts 58 60 and 59 61. The drop-braces 56 and 57, as well as 34, are pivoted adjustably in certain of several bearing-holes in uprights attached to the machine-

frame, as at 68 and at 69, pivot-bolts, such 50 as 66 and 67, being used. The inner ends or arms of each of these drop-braces are provided with studs 64 65, which are movable in a horizontal slot, such as 62, in the upper expanded portion of the rack-frame 50 51. This 55 rack-frame is supplied on each side with a rack with inwardly-extending teeth, said teeth being meshed into those of a pair of gears 1 and 2, the latter also meshing with each other and being supported on the horizontal shafts 60 13 and 14, set in bearings in the machine-frame 46. The bottom plate of the cores 30 31 has a downward extension 22, furnished with a threaded opening 70, in which is fitted the upper threaded end of the shaft 17. This 65 connection is supplied for the purpose of adjustment of the length of said shaft when necessary.

A crank 45 extends from the inner end of the sleeve 4 on the shaft 13 and is pivoted to 70 the lower end of the shaft 17. The bottom plate of the cores is maintained in line and prevented from sagging or warping under a torsional stress by means of upright guides 16, 18, and 19, moving in bearings 15, 20, and 75 21, respectively. A lever 3, with its attached handle-bar 5, is keyed to the shaft 13, while an auxiliary lever extends from the sleeve 4 and has an attached handle-bar 6. The sleeve 4 is rotatable about the shaft 13, but does not 80 move about said shaft unless the handle-bar 6 is disconnected from the handle-bar 5. For ordinary use the two handle-bars are connected together by means of a hasp 9, pivoted on the handle-bar 6, and which engages a 85 catch 8 on the handle-bar 5. The hasp is operated by means of a link 10, connected to the pivoted handpiece 12, which latter is supplied with a spring 11 for the purpose of keeping the hasp 9 normally in engagement 90 with the catch. The handle-bar 5 also has a dog 71, adapted to engage the teeth of the ratchet-bar 7, the latter being attached to the machine-frame.

The side plates 32 and 33 are capable of 95 horizontal adjustment within the uprights on the frame, as shown.

When the two handle-bars 5 and 6 are in

the position shown, being clutched together, and are together moved downward, the operation of the machine is as follows: The cores 30 and 31 are lowered by the action of the 5 crank 45 on the shaft 17, while the bottom plate 72 and the side and end plates 32 33 37 38 are moved, respectively, upward or outward by the action of the rising rack-bars 50 51. When the handle-bars are elevated, the said 10 actions are reversed. These are the ordinary movements of the machine; but at times it becomes necessary for the operator to lower the cores 30 31 independently of the ordinary action. In that case the hasp 9 is disengaged 15 from the catch 8, when the handle-bar 6 may be moved separately downward, moving along the rotatable sleeve 4 about the shaft 13, thus actuating alone the crank 45 and lowering the cores 30 31 without moving the bottom or 20 side and end plates of the mold. The object of this is to enable the operator to (when desired) separate the cores from the molded block just before the movement of the handle-bar 5 actuates the other parts of the machine. 25 This prevents sudden separation of the block from the cores, obviating consequent breakage of the soft block.

Having described my invention, what I claim as new, and desire to secure by Letters 30 Patent, is—

1. A machine for forming concrete building-blocks, consisting of the combination with a mold having swinging sides and ends, of a reciprocating core, a reciprocating bottom 35 plate having openings for the core, mechanism connecting and operating the core, the swinging sides and ends and the bottom plate, and a two-part lever adapted to actuate the core either simultaneously with or independently from the said sides and ends and bottom plate, substantially as shown and described.

2. A machine for forming concrete building-blocks, consisting of the combination of 40 a mold having swinging sides and ends, means for adjusting the position of said sides and ends, a reciprocating core, a reciprocating

bottom plate having openings for the core, mechanism connecting and operating the core, the swinging sides and ends and the bottom 50 plate, and a two-part lever adapted to actuate the core either simultaneously with or independently from the said sides and ends and the bottom plate, substantially as shown and described. 55

3. A machine for forming concrete building-blocks, consisting of the combination of a mold having swinging sides and ends, a reciprocating core, guides for said core, a reciprocating bottom plate having openings for 60 the core, mechanism connecting and operating the core, the swinging sides and ends and the bottom plate, and a two-part lever adapted to actuate the core either simultaneously with or independently from the said sides and 65 ends and bottom plate, substantially as shown and described.

4. A machine for forming concrete building-blocks, consisting of the combination of a mold having swinging sides and ends, means for adjusting the position of said sides and 70 ends, a reciprocating core, guides for said core, a reciprocating bottom plate having an opening for the core, mechanism connecting and operating the core, the swinging sides 75 and ends and the bottom plate, and a two-part lever adapted to actuate the core either simultaneously with or independently from the said sides and ends and the bottom plate, substantially as shown and described. 80

5. In a machine for forming concrete building-blocks, a separable two-part lever, adapted when connected together to actuate all the parts of said machine simultaneously and when separated to actuate the core independently 85 of the other mechanism, substantially as shown and described.

Signed at Waterloo, Iowa, this 21st day of May, 1904.

JOHN H. STEWART.
